COMBINED COMB AND CURLER

Leo Seldner, Rockville, Centre, N. Y., assignor to
 The Glembay Company, Inc., New York, N. Y.,
 a corporation of Delaware

Application April 14, 1938, Serial No. 201,885

1 Claim. (Cl. 132—35)

This invention relates to improvements in hair treating devices and has particular reference to a combined comb and curler.

An object of the invention is the provision of an improved device of simple and practical construction in which a comb is formed with an extension to provide a mandrel having a clamping member co-operating therewith to secure the end of a strand of hair thereto so that said strand 10 may be coiled about said element to form or reset a curl.

Another object is to mount a hair clamping member upon an extension of a comb in such manner that said comb and extension may be 15 interchangeably employed as handles for manipulating the device when curling and combing the hair, respectively.

The above and other objects will appear more clearly from the following detailed description 20 when taken in connection with the accompanying drawing which illustrates a preferred embodiment of the inventive idea.

In the drawing:—

Figure 1 is an elevation, partly in section, of 25 the device constructed in accordance with the invention.

Figure 2 is a top plan or edge elevation of the device, and,

Figures 3 and 4 are sections on the lines 3—3 30 and 4—4, respectively, of Fig. 1.

In its preferred form the device is shown as comprising a comb portion including the usual back 5 and teeth 6. At one end of the comb the same is provided with a reduced extension 7 substantially in alignment with the back 5 of the comb, and said extension is preferably tapered toward its outer end so as to constitute a mandrel about which a strand of hair may be coiled when the device is used as a curler, in which instance, the comb portion may be used as a handle to manipulate the device.

In order to secure the end of a strand of hair to the mandrel preliminary to winding said strand thereabout, the device further includes a clamping member 8 which is coextensive with the mandrel and which may be made of metal bent into channel formation as best shown in Fig. 3, so as to receive one edge of the mandrel when the member 8 is in clamping relation thereto. Adjacent one end of the clamping member 8 there are provided the opposed ears 9 between which extends the pivot 10 that also passes through the extension 7 to form a pivot for the member 8 whereby the same may be moved relative to the mandrel as indicated by the dotted lines in Fig. 1.

Means are provided for normally and yieldably maintaining the clamping member 8 in the operative position relative to the mandrel. For this

purpose the extension 7 at the inner end thereof contiguous to the back 5 and at its upper or outer edge is cut away or reduced as indicated at 11 to form a cavity into which the inner end of the clamping member 8 may be depressed in order 5 to separate said member from the mandrel and thus enable the end of a strand of hair to be introduced between said elements and clamped therebetween when the member 8 is restored to its normal operative position. To this end, use is 10 preferably made of a bowed leaf spring 12 one end of which may engage in the channel of the inner extremity of the member 8 while the other end of said spring is seated in an elongated recess 13 formed in the bottom of the cavity 11 15 and of a width substantially that of the spring so that the latter will be securely held in place. Said spring thus acts to exert an outward pressure on the inner end or handle portion of the clamping member 8 so that the remainder of said member 20 will be yieldably forced into engagement with the mandrel. However, when it is desired to spread the mandrel and clamping member so that the end of a strand of hair may be introduced therebetween, the handle portion of said member 25 8 may be depressed into the cavity 11 against the action of the spring 12 and when said pressure is relieved the member 8 will then clamp the hair to the mandrel. The strand may then be wound about the mandrel and clamping member in the 30 usual manner, either for forming a curl or resetting the same. When the curl has been properly wound, the mandrel and clamping member may be separated to withdraw the device from the curl and, if desired, a suitable fastener such 35 as a bobby pin may be attached to the curl to hold it in place. When the device is to be used as a comb, the extension 7, together with the clamping member 8, may be employed as a handle for manipulating the comb.

What is claimed is:

A combined comb and curler device comprising a comb portion and an extension projecting from one end of said portion to form a mandrel, said extension at its inner end contiguous to the inner 45 end of said comb portion being formed with a cavity extending the width of said mandrel and provided in the bottom of said cavity with a recess of less width than said cavity, a clamping member pivoted to said mandrel and having a handle overlying said cavity so that the handle can be depressed into said cavity, and a spring seated in said recess and extending outwardly therefrom for engagement with said handle to normally urge the clamping member into cooperative relation 55 with said mandrel.

LEO SELDNER.
